UNITED STATES PATENT OFFICE.

STANLEY ALEXANDROWICZ, OF TRENTON, NEW JERSEY.

METALLIC TIE AND RAIL SUPPORT.

Application filed January 31, 1924. Serial No. 689,734.

To all whom it may concern:

Be it known that I, STANLEY ALEXANDROWICZ, a citizen of Poland, residing at Trenton, in the county of Mercer and State 5 of New Jersey, have invented certain new and useful Improvements in Metallic Ties and Rail Supports, of which the following is a specification.

This invention relates to certain new and 10 useful improvements in metallic ties and rail supports and has for its primary object to provide a railroad tie of sheet metal formed from a blank and bent into the general formation of a tie with rail supporting means at each end thereof.

A further object of the invention is to provide a metallic tie and rail support of the type above set forth wherein the rail support is in the form of wooden blocks 20 mounted in each end of the sheet metal tie and upon which the rail is directly seated, the anchoring bolts or spikes for the rail securing the rail supporting blocks in position in the tie.

With the above and other objects in view that will become apparent as the nature of the invention is better understood, the same consists of the novel form, combination and arrangement of parts hereinafter more 30 fully described, shown in the accompanying drawing and claimed.

In the drawing, wherein like reference characters designate corresponding parts throughout the several views,

Figure 1 is a top plan view of a metallic tie and rail support constructed in accordance with the present invention,

Figure 2 is a side elevational view, partly broken away and shown in section,

Figure 3 is a cross-sectional view taken on line III—III of Fig. 2, and

Figure 4 is a fragmentary plan view of one end of the blank from which the sheet metal tie is formed.

Referring more in detail to the accompanying drawing, there is illustrated a metallic tie and rail support, the tie being formed from a blank of sheet metal and embodying a central longitudinal base section 1 carrying side extensions 2 that are adapted to be folded upon the dotted lines as indicated by the numeral 3 to form the tie base and side walls as shown in Fig. 2. An end flange 4 is carried by each end of 55 the central base section 1 and is foldable upon the dotted line 5.

The side portions 2 are cut upon the curved lines 6 reducing the diameter of the side portions intermediate the ends of the blank and providing tie flaps 7 that are 60 spaced by the cutaway portion 8 that extends from the outer edges of the flaps 7 into the adjacent side portion 2. The flaps 7 are foldable upon the dotted lines 9 and the opposed side edges 10 of said flaps are 65 notched as at 11 for purposes presently to appear.

The blank shown in Fig. 4 is first folded upon the dotted lines 3 to position the side portions 2 perpendicular to the base portion 1. The side flaps 7 are then folded upon the dotted lines 9 to lie parallel with the base section 1 and the end flanges 4 are then perpendicularly bent upon the dotted lines 5. With the flaps 7 so bent, the edges of the opposed flaps are adjacently positioned as shown in Fig. 1 and a wooden tie supporting block 12 is mounted upon the central portion of the base 1 and is then moved outwardly to underlie the flaps 7 as shown in Fig. 2, movement thereof being limited by the end flanges 4. The rail 13 is then mounted upon the rail supporting block 12 between the side walls 10 of the flaps 7 and rail anchoring spikes 14 are driven into the rail supporting block 12, the spikes 14 passing through the notches 11 and permitting the adjacent edges 10 of the flaps to contact the opposite side edges of the base flanges of the rail 13. 85 The spikes 14 employed for anchoring the rail to the supporting block 12 also prevent shifting movement of the block with respect to the tie resulting in a strong and durable sheet metal railroad tie and rail 90 supporting block.

From the above detail description of the invention, it is believed the construction and operation thereof will at once be apparent, and while there is herein shown and described the preferred embodiment of the present invention, it is nevertheless to be understood that minor changes may be made therein without departing from the spirit and scope of the invention as 105 claimed.

What is claimed as new is:—

In a metallic tie and rail support, a tie struck from a blank of sheet metal and having a central base portion, side walls 110 carried thereby, inturned flaps carried by the ends of the side walls, a rail support-

ing block mounted in each end of the tie with the flaps overlying the same, a spike-retained rail supported on the block between the opposed flaps with the spikes entering the blocks to hold the same in position on the tie, said flaps being arranged in pairs at each side of the block and having notches in their opposed edges to accommodate the rail anchoring spikes, and

upturned end flanges carried by and extending the full width of the opposite ends of the central base portion engaged by the outer ends of the blocks and the end edges of the side walls to assist in holding the blocks positioned in the tie.

In testimony whereof I affix my signature.

STANLEY ALEXANDROWICZ.
